UNITED STATES PATENT OFFICE.

EDWARD G. JAY, OF PHILADELPHIA, PENNSYLVANIA, ASSIGNOR OF
ONE-HALF TO SAMUEL S. JAY, OF ABERDEEN, MARYLAND.

BUCKLE.

SPECIFICATION forming part of Letters Patent No. 592,733, dated October 26, 1897.

Application filed December 15, 1896. Serial No. 615,744. (No model.)

To all whom it may concern:

Be it known that I, EDWARD G. JAY, a citizen of the United States, residing at Philadelphia, in the county of Philadelphia and 5 State of Pennsylvania, have invented certain new and useful Improvements in Buckles, of which the following is a specification.

According to this invention I make a buckle in two parts hinged together and detachably 10 connected, the arrangement being such that when in use the two members of the buckle are so related that they cannot possibly be separated, but when properly manipulated and made to assume a position relatively to 15 each other which they never assume when in use can be very quickly detached. The buckle also is so arranged as to be tightly secured to the strap or straps to which it is applied without puncturing the strap or otherwise weakening it.

My improved buckle may be applied to different parts of the same end of a strap or to the opposite ends thereof. It may be applied to bridles, reins, belts, horse-blankets, and, 25 in fact, to very many different kinds of straps and belts or other like things where buckles are used and where it is desirable to quickly unbuckle as well as tightly and securely lock the strap.

30 In the accompanying drawings, Figure 1 shows how my improved buckle is applied to a bridle and bit. Fig. 2 is a front elevation of the buckle applied to a bridle, rein, or the like. Fig. 3 shows a horizontal section through 35 the buckle, the strap being in plan. Fig. 4 shows a perspective view of the two members of the buckle.

The precise shape of the buckle members is not important, nor is it necessary that they 40 should be manufactured in any particular way or produced from any particular material. Preferably each member of the buckle is substantially rectangular in outline, the member A consisting of a rectangular frame 45 surrounding a central rectangular opening a, bridged by a cross-piece b, which is preferably triangular in cross-section, so that it may present a sharp edge to the strap and thus prevent it from slipping. On the rear side 50 the member A is provided with a loop c to aid in holding the strap in place, as hereinafter

explained. A cylindrical lug B is formed on one end of the member A, and it is provided with a vertically-arranged cylindrical socket d, with which communicates a vertically- 55 arranged slotted opening e, having parallel sides. This opening e may be arranged in either the front or rear side of the buckle member A, and in either case it is arranged at an angle of less than ninety degrees with the 60 body portion of the buckle member. Fig. 3 shows this opening e formed on the face of the buckle member A. The dotted lines e' in said figure illustrate the position of the said opening when arranged on the rear side 65 of the buckle member A. This latter position is preferable, inasmuch as the strap Y will close the opening e when the two members have been connected, and thus all possibility of the parts becoming accidentally disengaged will be avoided. This object is further facilitated by the position of the loop c, 70 which aids in holding the strap Y against the opening e, no matter what position the buckle may assume. The opening is arranged as 75 shown in dotted lines in Fig. 3, as when thus arranged the strap Y will close the opening and more securely lock the buckle members together. The other buckle member C is also substantially rectangular in outline and has 80 a rectangular central opening f. The two parallel upright frame-pieces g h are preferably circular in cross-section. The frame-piece h extends all the way to the end of the bottom member C, as shown in Fig. 4, and 85 this frame-piece is adapted to enter the socket d in the lug B. At its opposite end the frame-piece h is provided with an enlarged cap i.

When the buckle is applied to a bridle, the 90 parts are arranged as shown particularly in Figs. 2 and 3. The end of the strap is passed through the opening f of the member C and is looped and attached in the usual way, as indicated. The strap also passes through the 95 loop c, then through the opening a, over the cross-piece b, and again back through the opening a. By this arrangement the strap is securely fastened to the member A and is not apt to slip.

100 Fig. 2 shows the buckle members in position for use. The two members are hinged

so as to have a slight oscillating movement, but when the reins are tight, as shown in Fig. 1, they are practically rigid. It will be understood that when applying the reins to a bit the end of the strap containing the member C is passed through the ring, as shown in Fig. 1, and the frame-piece h is arranged in the socket d. It is inserted in the socket d by being arranged above the lug and then slid 10 in endwise, the bottom piece j of the member C being of such width as to readily pass down through the slot e. The cap i arrests the downward movement of the member C when it has come into proper alignment with the member A.

The buckle should always be arranged with the two members in the relative positions indicated—that is, with the cap i above the socket—so that if by any chance the buckle 20 members should assume the position indicated in Fig. 3 they could not become separated by gravity, but would have to be positively manipulated.

This buckle is found to be strong and durable and easily operated and is not so apt to be broken as a snap-hook, which is sometimes used for the same purpose.

I claim as my invention—

1. A buckle comprising two members hinged together, one of said members having a central opening bridged by a cross-piece, and having also a cylindrical lug having a cylindrical socket communicating with a vertically-arranged slotted opening having parallel sides 35 extending at an angle of less than ninety de-

grees, with the plane of the buckle, and the other buckle member having a central opening and a cross-piece adapted to fit the socket in the other buckle member, whose cylindrical lug is so formed as to rotate freely about 40 said cross-piece as an axis, and having also an end piece adapted to traverse the slot and adapted to be disconnected therefrom at only one position, and a cap to limit the movement of one buckle member relatively to the other. 45

2. A buckle comprising two members hinged together, one of said members having a rectangular frame with a central opening bridged by a cross-piece, and a loop on its rear side, and provided also with a lug having a central, vertically-arranged socket communicating at its rear face with a slotted opening having parallel sides, the other buckle member consisting of a rectangular frame having a side piece adapted to fit the socket of the other buckle member, and an end piece adapted to slide in the slotted opening therein, and having also a cap to limit the movement of one buckle member relatively to the other in combination with a strap attached to one buckle 50 member and passing through the loop of the other buckle member, so as to close the slotted opening and prevent the parts from becoming disengaged.

In testimony whereof I have hereunto subscribed my name.

EDWARD G. JAY.
